UNITED STATES PATENT OFFICE

WILLIS P. THOMAS, OF DETROIT, MICHIGAN, ASSIGNOR TO DIAMOND POWER SPECIALTY CORPORATION, OF DETROIT, MICHIGAN, A CORPORATION OF MICHIGAN

BOILER CLEANER

Application filed November 6, 1922. Serial No. 599,330.

This invention relates to boiler cleaners and refers more particularly to boiler cleaners of the type in which a rotatable blower pipe having jet nozzles is used for cleaning the soot from the boiler tubes or other surfaces to be cleaned.

One of the main objects of the invention is to provide an improved construction of a floating mounting of a unit so that binding of the unit when being turned is prevented. Other objects of the invention are to provide an improved sealing for the opening through which the blower pipe or unit extends, a resilient support for the blower pipe header, and means for providing a supply of cleaning fluid to the blower pipe during continued movement of the blower pipe in one direction. The invention further resides in such features of construction and arrangements and combinations of parts as will more fully hereinafter appear.

In boiler cleaners of the general type above described the unit is hung from or otherwise mounted upon the tubes of the boiler. Since the boiler tubes in expanding and contracting under heat tend to move relative to the boiler setting means have heretofore been provided for permitting the blower unit to pass through the boiler setting in such a manner as to prevent the binding of the blower unit when being turned. The present construction not only provides improved means for sealing the opening through which the blower pipe extends but it also provides a resilient mounting for the blower pipe head in which the tubes are relieved from the weight of the head without interfering with the relative movement of the blower unit with reference to the boiler setting.

In the drawings:

Fig. 1 is a side elevational view showing several blower units embodying my invention applied to a water tube boiler.

Fig. 2 is an enlarged vertical section partly in elevation through one of the units.

Fig. 3 is an end view of the parts shown in Fig. 2.

Figure 4 is a side elevation showing the valve actuating cam;

Figures 5 and 6 are elevational views of the cam at right angles with Figure 4;

Figures 7, 8, 9 are respectively section views along 7-7 in Figure 4, 8-8, and 9-9 in Figure 5;

Figure 10 is a detail fragmentary view illustrating the trigger pivotal mounting.

Describing in detail the particular embodiment of my invention shown in the drawings, 1 designates a boiler of the Stirling type, although the invention is not limited to the particular form of boiler shown. In this boiler a plurality of upper drums 2 are connected to a lower drum 3 by a series of banks of tubes 4. For cleaning the soot from these tubes a plurality of blower units 5 are provided, these blower units being distributed in certain predetermined portions of the boiler so as to clean the soot from the tubes of the boilers without striking against the baffles or other parts which might be injured, while accomplishing this result with the smallest number of units practical.

The blower units are of the type shown in Figure 2 in which there is a rotatable blower pipe or tubular member 6 connected by a coupling 6^a to the tube swivel 7 which latter is journaled into the non-rotatable part or head 8. This head is formed with a flanged goose-neck 9 which at its lower end is secured to a flange 10 on the stationary inlet pipe 11. To provide a certain degree of resiliency the latter is preferably provided with bend 12' in the pipe for yielding a limited amount as hereinabove described. Steam to the blower unit 6 from the inlet pipe 11 is controlled by a valve 12 which seats against a valve seat 13 and is normally held against its seat by a valve spring 14. The construction of parts is such that the valve 12 is normally held to its seat 13 by the spring 14 and is only opened when the valve stem 15 is forced down by the trigger 16, the latter being operated by a cam 17, which rotates with the blower pipe 6. It will be noted from Figure 3 of the drawings that the cam 17 is a 360° cam, the inset portion 17' of the cam permitting trigger 16 to seat valve 12 at one point of the cam only, that point occurring in the position shown in Figure 3. This blower pipe 6 is

provided with a plurality of jet nozzles 18 which discharge steam against the surfaces of the boiler tubes 4.

Referring particularly to Figures 4 to 9, I have shown in detail the construction of the cam 17. In these views the cam is formed between points 17^a and 17^b with two tracks or faces 17^a and 17^b for convenience referred to as the inner and outer tracks respectively. The inner track 17^a is formed with the inset portion 17^c aforesaid which in the clockwise rotation of the cam, as seen in Figure 4, is engageable with trigger 16 which is depressed thereby unseating the valve 12. Upon continued clockwise rotation of the cam the upper trigger end will ride on the single track 17^b which freely communicates as shown in Figure 6 with both tracks 17^a and 17^b, the valve being held unseated. When the cam nears the completion of a 360° revolution, the trigger end is shunted on to the track 17^b by the upstanding guide rib 17^d, thus preventing the trigger from moving to restore the valve to seated position. Further clockwise rotation of the cam causes the trigger to move in track 17^b which at point 17^d communicates with the single track 17^a and if desired, this cycle of 360° rotation may be repeated as many times as desired. When it is desired to seat the valve after one or more revolutions of 360° each, the operator rotates the cam until the trigger end passes the point 17^a whereupon the cam is moved in the reverse direction, permitting the trigger to ride down the inset portion 17^c and off the inner end thereof. The cam is thus in the nature of a spiral cam.

As shown in Figure 10, the trigger is pivoted upon a pin 17^e supported by a stationary bracket 17^f. 17^e is a spring normally yieldingly urging the trigger toward the face of the gear and in position to be engaged by the lower inset end of the cam, the spring also permitting yielding of the trigger when the latter is moved by the rib 17^d from the track 17^b to the outer shunt track 17^a as aforesaid. The lower end of the trigger is provided with an opening 17^g which is somewhat larger in diameter than that of the pin 17^e passing therethrough permitting a slight lateral rocking movement of the trigger in moving to the track 17^b as will be readily understood. The cam 17 may be secured to the face of gear by suitable means such as fasteners 17^h.

The blower pipe 6 extends through a wall box 19 and is supported by clamps 20 from the boiler tubes 4. Inasmuch as these tubes, under expansion and contraction move relative to the boiler setting, the side boiler wall 21 is provided with an enlarged aperture 22 in which the wall box 19 seats. The inside diameter of the latter is considerably larger than the outside diameter of the blower pipe 6 so that the latter is free to move with refer-

ence to the boiler setting. For sealing the opening in the wall box 19 there is provided a sealing plate 23 which is normally held against the wall box flange 24 by means of a spring 25.

In order to prevent the entire weight of the blower pipe head being carried by the inlet pipe and the boiler tubes there is provided a novel spring suspension as follows: Extending outwardly from the wall box flange 24 is a cap screw 26 which extends through slots 27 in a floater cap 28. Housed within the latter is a spring 29 which at its lower end abuts against the cap screw 26 and at its upper end against a retaining disk 30. The position of the latter, with reference to the top of the floating cap, is adjustable by a set screw 31 so that the amount of tension of the spring 29 can be adjusted. The floater cap 28 carries the sealing plate 23 which is loosely sleeved upon the blower pipe 6 and thus through the swivel tube 7 carries the head 8.

Also extending outwardly from the wall box flange 24 and carried thereby is a stud 32 which extends through a slot 33 in the bracket 34. The slot 33 is of considerably larger diameter than stud 32, thus permitting bracket 34 to move freely in the plane of the boiler wall while preventing movement transversely thereof. The bracket is secured at its lower end by a cap screw 35 and its upper end by a tie rod 36 to the head 8. In the above construction, it will be noted that the head, as well as the blower unit 6, has a spring suspension or yielding support from the wall box and is thus in reality carried by the side boiler wall while still free to move with reference thereto. Also the return-bends 12' in the inlet pipes permit sufficient yielding with reference to the stationary pipe parts so as to make a substantially full floating head arrangement. Because of the high temperatures to which the blower pipe is subjected and the possibility of its warping, the above described mounting is one of great material advantage. A suitable packing gland 39 and packing 40 are provided, sealing the swivel joint between the blower pipe and the head. For rotating the blower pipe with a slow but steady motion a gear 41 is carried by a collar 42 fixed on the blower pipe, this gearing meshing in turn with a pinion 43 fixed to rotate with the sheave wheel 44 mounted on the tie rod 36 and operated by chain 45 extending to a convenient position near the blower end of the boiler. By this arrangement the blower pipe is not only conveniently rotated but the valve controlling the supply of steam to such unit is also automatically operated from the same control mechanism.

In rotating the blower pipe 6, the sheave 44 is rotated by chain 45 thereby causing pinion 43 to rotate gear 41. Rotation of the gear 41 also causes rotation of blower pipe 6 and

in timed relation therewith causes cam 17 to act upon trigger 16 to hold valve 12 unseated for a 360° revolution of the blower pipe 6 and cam 17.

5 What I claim as my invention is:

1. In a boiler cleaner, a rotatable blower element, a cleaning fluid supply pipe communicating with said element to supply cleaning fluid thereto, a valve controlling the passage of cleaning fluid to said blower element, a cam actuated upon rotation of the blower element, means actuated by the cam upon rotation of the blower element in one direction for unseating the valve, said cam having provision for acting on said means for holding the valve unseated for 360° of rotation of said blower element in the said direction, while permitting said valve to close upon rotation of said blower element in the other direction.

2. In a boiler cleaner, a rotatable blower element, a cleaning fluid supply pipe communicating with said element to supply cleaning fluid thereto, a valve controlling the passage of cleaning fluid to said blower element, a cam actuated upon rotation of the blower element, means actuated by the cam upon rotation of the blower element in one direction for unseating the valve, said cam having provision for acting on said means for holding the valve unseated for one or more complete rotations of the blower element in the said direction while permitting said valve to close upon rotation of the blower element in the other direction.

3. In a boiler cleaner, a rotatable blower element, a cleaning fluid supply pipe communicating with said element to supply cleaning fluid thereto, a valve controlling the passage of cleaning fluid to said blower element, a cam actuated upon movement of said blower element and means actuated by the cam for unseating the valve when the blower element is turned in one direction, said cam being formed to act on said means for holding the valve unseated for 360° of rotation of said blower element, said cam also being formed upon rotation of the blower element in the opposite direction from that aforesaid to release said means to permit seating of the valve.

4. In a boiler cleaner, a rotatable blower pipe, a cleaning fluid supply pipe communicating with said blower pipe, a valve controlling the passage of the fluid to said blower pipe, a cam for actuating the valve mounted to rotate with the blower pipe, means for rotating the blower pipe to cause said cam to fully unseat the valve in timed relation with the rotation of the blower pipe to supply fluid to the blower pipe, said cam being formed to maintain said valve fully unseated during a 360° rotation of said blower pipe but being movable to a position to permit seating of said valve.

5. In a boiler cleaner, a blower pipe, a cleaning fluid supply pipe communicating with said blower pipe, a valve controlling the passage of the fluid to the blower pipe and provided with an actuating member, a 360° cam mounted to rotate with the blower pipe and adapted to cooperate with said member to actuate said valve, and means for rotating said cam to fully unseat the valve for supplying fluid to said blower pipe for a period corresponding to 360° of rotation thereof, said cam being movable in a direction to permit seating of said valve.

6. In combination a blower element mounted for unlimited movement in two directions, means for moving said element in the said two directions, a valve for controlling the flow of cleaning fluid to said element, and means operable upon movement of said blower element in one of said directions to open said valve and to hold said valve open during the continued movement of said blower element in the said direction, said means being also operable to permit closing of said valve upon movement of said blower element in the other direction.

7. In combination, a blower element mounted for unlimited rotation, means for rotating said element, a valve for controlling the flow of cleaning fluid to said element, and means operable on rotation of said blower element in one direction to open said valve and to hold said valve open during the continued rotation of said blower element in the said direction, said means being also operable to permit closing of said valve upon a reverse rotation of said blower element.

In testimony whereof I affix my signature.

WILLIS P. THOMAS.
